SHOE FOR DRIVING PILES

Carlos Guillermo Cleesattel, Olivos, Argentina,
assignor of one-third to Hugo C. Gollmer,
New York, N. Y.

Application September 27, 1937, Serial No. 165,882
In Argentina September 28, 1936

4 Claims. (Cl. 61—57)

This invention concerns a method of and means for constructing concrete piles "at site," i. e., at the location of their ultimate use; more particular it involves an improved adaptation of driving tubes and guide shoes provided upon such tubes for the said purposes.

It is customary in this art to ram a drive tube into the ground at the desired location the tube being provided at its lower end with a suitable closure, which is called a shoe. After the tube has been rammed into the earth to a certain depth, a limited quantity of concrete is filled into the tube and is compressed by a suitable ram vertically reciprocated in the interior of the tube. The driving tube may at the same time be driven further down into the earth, either by blows applied to the upper end of the driving tube, or by the force transmitted to the tube from the concrete in the interior of the tube when the concrete is compressed by the stroke of the ramming device.

After the tube has been lowered to the depth to which the concrete is eventually to extend, it is pulled out step by step, the plastic concrete being simultaneously added to the first-mentioned quantity into the tube and being compressed by the ramming device. As the tube is being raised, the concrete emerging from the bottom thereof spreads into the surrounding layers of earth, thus forming projections laterally protruding from the core of the finished concrete pile which anchor the concrete pile and render impossible a vertical displacement thereof.

Aside from other disadvantages, the procedure requires an unnecessary excess of power in the ramming operation, because the friction of the large exterior surface of the tube and contacting with the inner wall of the hole in the earth offers a high frictional resistance to the descent of the tube. Thus comparatively heavy pile driving apparatus has to be used in order to ram down the driving tube.

Another objectionable and frequently encountered disadvantage is the sliding off or lateral shifting of the driving tube. One reason for this is a varying consistency of the strata of earth.

These and other disadvantages, which will be recognized hereinafter, are avoided by the instant invention, as now to be explained by way of an example. The description is to be interpreted as an illustration and not as a limitation of the invention.

The figures of the accompanying drawing show such example at progressive stages of oper-

ation; all the views are vertical detail cross-sections extending substantially through the central axis of the driving tube and the potential pile.

The view of Fig. 1 is taken at the time of the beginning of the operation, e. g., just after the first measure of concrete has been introduced into the lowered driving tube.

Fig. 2 shows the driving tube at its lowermost position, i. e., when the driving proper has been completed.

Fig. 3 depicts the set-up after the first major step of withdrawal of the driving tube.

Fig. 4 is an underground detail at a still farther stage of withdrawal of the driving tube.

In all figures like numerals are applied to similar parts.

A novel driving tube 10 of this invention may comprise a cylindrical neck portion or upper part 11 and a cylindrical lower part 12, part 11 being smaller in diameter than part 12. The head portion or lower part 12 is concentrically fastened to the upper part 11 by any suitable means, for instance by way of a threaded bushing 13, which is shown to be conically flared on the outside and on the inside, at the upper and the lower end, respectively. The upper end 14 of the upper part 11 may be suitably attached, e. g., by thread, either directly to a retaining collar 15 forming part of a suspension device and adapted to be suspended from cable 22 (Fig. 1) or to one or more extension parts 16, the last of which may be suspended by way of a collar 15 or the like (Figs. 2 and 3). In order to avoid that a collar 15 or an extension part 16 strip the connecting thread and slide over the part 11 or 16 below the driving tube 10, an outer shoulder may be provided for end thrust upon the outside near the upper ends of said parts 11 and 16; thus a collar 17 may be affixed, e. g., welded underneath the upper end 14 onto the parts 11 and 16, on their exterior circumferences.

The length of the lower part 12 is preferably several times larger than the diameter thereof, in order to insure proper guidance in the earth of the whole descending driving tube 10.

A novel guide shoe 18 may cooperate with the novel drive tube 10. This guide shoe 18 comprises a raised center portion shown in the drawing as a hollow cone. This shoe may be provided with a rim 19 with an outside diameter slightly larger than that of the lower part 12 of the drive tube 10. This shoe serves as a closure for the tube, the rim seating as a flange onto the open bottom end of the lower part 12 of the driv-

ing tube 10, so that it represents a tool with a shoal end. The apex of the cone-shaped shoe 18 may point up into tube 10, as shown.

It is easily seen that there is no friction between the neck portion or the upper contracted part 11 (or extension 16) of the driving tube 10 and the wall 30 of the hole formed by the descending shoe 18. There is friction only between the lower part 12 and the wall 30 of the hole. Thus the losses caused by friction during the operating of this device are small in comparison with driving tubes of the prior art.

Experience has further shown that the special shape of the guide shoe 18 insures that the whole sliding tube 10 moves vertically downward without any lateral displacement.

It is easily seen, and has been proved by experience, that the cone of the guiding shoe 18 is instrumental in forcing the concrete radially out of the lower part 12 of the driving tube 10, so that the concrete spreads like a mushroom. The shoe acts as a spreader, greatly facilitating and accentuating the formation of the projection 27 at the foot of the finished pile as will be more fully described hereinafter.

The method of using the driving tube 10 of this invention is progressively illustrated in Figs. 1 to 4. The earth is first excavated to a certain depth below the surface 20, and the driving tube 10, and the guide shoe 18 are positioned in the excavation (Fig. 1). But before this is done the hollow part of shoe 18 is filled with sand 21 or other suitable anti-friction material. During this part of the work, the driving tube 10 may be held in an upright position by the ropes or cable 22 operated by and depending from any suitable means, for instance a winch and a boom, respectively (not shown). The interior of the driving tube 10 is then filled up to a low level (Fig. 1) with a suitable quantity of concrete 23.

Now the ram 24, which is arranged for reciprocation by way of a rope 25, is put to work in the manner well known in the art, ramming the concrete 23 in the driving tube 10. The pressure is transmitted to the guide shoe 18 and drives guide shoe 18 down into the earth. Due to its weight the driving tube 10 moves down, following the descending guide shoe 18, the holding ropes 22 being paid out in accordance with the progress of the downward movement of the driving tube 10. The operation is continued until the guiding shoe 18 has reached the desired depth (Fig. 2), the driving tube 10, and more particularly the neck portion thereof, being elongated at intervals during the operation, if necessary, by insertion of one or more extensions 16.

After the desired depth has been reached, the driving tube 10 is withdrawn by means of cable or ropes 22 to an intermediate level 26 (Fig. 3), and the ram 24 preferably continues to operate during

this phase of the work. The concrete 23 which had been stored in the lower part 12 of the driving tube 10 is forced out of the tube into the soft layers of the earth. The conical apex of the guide shoe 18 radially disperses and squashes the extruded material, and a lowermost and biggest concrete head 27 is formed at the foot of the pile, so that, after the concrete has hardened, the pile is firmly founded and rooted in the ground.

But in the meantime another charge 19 of concrete has been filled and rammed into the driving tube 10; the tube is again withdrawn; and ram 24 and lifting ropes 22 are simultaneously operated. As before, the concrete is impacted, and forced to spread radially into the soft layers of the earth, forming another peripheral projection 31 at a higher level of the pile (Fig. 4).

The procedure is repeated until the whole pile has been formed, and will be noted that the restricted neck 11, 16 also facilitates the withdrawal of tube 10.

As customary, reinforcing cages comprising for instance iron rods 28 and cross members 32 may be inserted into the driving tube 10 during the formation of the pile.

Having thus described my invention in detail, yet I do not wish to be limited thereby, except as the state of the art and the appended claims may require, for it is obvious that various modifications and changes may be made in the form of embodiment of my invention, without departing from the spirit and scope thereof.

What I claim is:

1. A shoe fitting adapted to close the lower end of a driving tube when said shoe is fitted onto said tube and having a central raised portion on said shoe adapted to extend into said tube and serving to spread apart concrete extruded from said tube onto said shoe.

2. A shoe for closing the lower end of a driving tube for constructing concrete piles, comprising a flat rim portion serving as a flange and a conical central portion arising from said rim portion with a root diameter fitting the tube and serving to spread concrete extruded onto said shoe from said tube.

3. As a shoe for a driving tube for concrete piles, a hollow cone, the apex at said cone serving to spread material extruded from the tube, and the hollow bottom of said cone serving to receive granules facilitating the driving.

4. Constructing a concrete pile, comprising driving a conical hollow shoe ahead of a driving tube, but with the apex of the shoe extending into the tube, into the ground and ramming concrete onto the apex of said shoe so that the concrete is subterraneously spread and squashed by said shoe when the ramming is continued after the tube has at least partly been withdrawn.

CARLOS GUILLERMO CLEESATTEL. 60
